UNITED STATES PATENT OFFICE.

FREDERICK EDWARD HEINIG, OF LOUISVILLE, KENTUCKY, ASSIGNOR OF TWO-THIRDS TO CURRAN POPE AND ALFRED THRUSTON POPE, OF LOUISVILLE, KENTUCKY.

SHEET-METAL FASTENING-CLEAT.

SPECIFICATION forming part of Letters Patent No. 699,311, dated May 6, 1902.

Application filed August 23, 1901. Serial No. 73,068. (No model.)

To all whom it may concern:

Be it known that I, FREDERICK EDWARD HEINIG, residing at Louisville, in the county of Jefferson and State of Kentucky, have invented certain new and useful Improvements in Sheet-Metal Fastening-Cleats, of which the following is a specification, reference being had therein to the accompanying drawings.

This invention relates to sheet-metal cleats, holdfasts, or cover-fastenings for barrel-heads, box ends, &c.

The object of the invention is to produce a durable and serviceable fastening entirely from sheet metal by which wooden cleats and nails may be entirely avoided.

Figure 1 is a diagram of a sheet, showing in dotted lines the cuts and bends to produce a cleat. Fig. 2 is a plan of the finished cleat according to one modification of my invention, and Fig. 3 is an elevation of the same. Fig. 4 is an end view showing modification of holding-points. Fig. 5 is a perspective view of one of my cleats applied to a box-head. Fig. 6 is a broken section of barrel or box side 25 and head with cleat applied. Fig. 7 is a broken section of right-angled cleat applied to a box. Fig. 8 is a perspective view of a cleat like that of Fig. 5, except for curvature, for use on a barrel.

The numeral 1 indicates a sheet of steel or similar metal, preferably galvanized on both faces. Such a strip is divided, and the rectangular strip is bent on line 2 parallel with the edges, so that it has two flanges 3 and 4, which flanges project from line 2 at such an angle as the circumstances warrant. For a box the cleat is straight from end to end. For a barrel it is slightly curved in direction of its length. The strip after bending has the form 35 of a cleat. It must have sufficient rigidity to hold a barrel or box head in place, as the holding effect of the cleat depends on its rigidity. One of the flanges, 4, is left plane and unperforated. The other flange, 3, has a plurality of triangular projections or "holding-points" struck therefrom. Preferably these points are in pairs. Figs. 3 and 8 show one

pair of points (marked 6) cut from the body of flange 3 at the edge thereof and extending backwardly with reference to flange 4, 50 the flat faces of these triangular projections or points being vertical when the cleat is in holding position, as in Figs. 5 and 7. Another pair of triangular projections or points (marked 5) have their bodies struck from 55 flange 3 near the bend, and these points have their flat faces horizontal in similar relation. In every case all the points are cut or struck from flange 3 and extend backward with reference to the direction of flange 4. 60

The cleat is applied to a box or barrel by means of a peculiar tool, which acts as a clamp and inserts all the points at once. The flange 4 lies on the barrel or box head when the cleat is about to be affixed, and the ends 65 of points 5 6 are against the chime of the barrel or the corresponding projecting side of the box. Then as the tool forces the points 5 6 into the barrel-stave or box side (chime) the flange 4 slides along on the head, and 70 comes to holding position, as shown in Figs. 5, 6, and 7, according to the construction of the cleat and the manner of using the tool. When the points are arranged with their flat faces at right angles to each other, as in Figs. 75 2, 3, 4, 5, 6, 8, the points brace each other and hold more firmly in the wood than if all the points were in one plane, since some of the points present edges and others flat faces in the direction of the grain of the wood. 80

The cleat is struck up and the points produced either at one operation or by a series of operations by mechanism well known to mechanics.

An important feature of the invention is the 85 doing away with nails, which have many objections, as known to the trade; also, the doing away with the common triangular wooden cleat, which is often employed with barrels and boxes in position similar to this cleat and 90 usually held by nails, although sometimes held both by nails and by sheet-metal fasteners, as shown in patent to Baker, No. 510,761, of December 12, 1893.

What I claim as my invention is—

A cleat composed of a rectangular plate of metal bent on a line parallel to its edge to form two flanges, one flange being plane, the

5 other flange having points struck from its body with their faces in the plane of the plane flange but projecting in opposite direction, and having also points struck from its edge with their bases perpendicular to the plane

flange, and extending in reverse direction to from the plane flange.

In testimony whereof I affix my signature in presence of two witnesses.

FREDERICK EDWARD HEINIG.
